CLAIM

The ornamental design of a roof gutter, as shown and described.

DESCRIPTION

FIG. 1 is a top plan view of a roof gutter showing my new design;

FIG. 2 is a bottom plan view thereof;

FIG. 3 is a side elevational view thereof;

FIG. 4 is a side elevational view showing the side opposite that shown in FIG. 3;

FIG. 5 is an end elevational view thereof;

FIG. 6 is an end elevational view showing the end opposite that shown in FIG. 5;

FIG. 7 is a perspective view taken from the top and one end thereof;

FIG. 8 is a perspective view taken from the bottom, one end and one side thereof.

The gutter has been broken away in FIGS. 1 through 4, 7 and 8 to indicate indeterminate length.

FIG. 1.**FIG. 2.****FIG. 3.****FIG. 4.**
